UNITED STATES PATENT OFFICE.

ALBERT H. WALKER, OF KENILWORTH, ENGLAND, ASSIGNOR TO CHARLES TORRES
WEYMANN, OF PARIS, FRANCE.

VEHICLE BODY.

Application filed October 2, 1924, Serial No. 741,095, and in Great Britain October 3, 1923.

This invention relates to bodies for automobiles and the like, and more particularly to that type of flexible body which is designed to warp or weave with the chassis frame body. Heretofore in this type of body, such as the well-known Weymann body (disclosed in U. S. Patent No. 1,519,093, granted December 9, 1924), it was thought necessary to avoid curved or round-
10 ed corners or angles, such as between the top, back and sides of the bodies, and the bodies were designed along straight line principles, sharp corners and angles being formed between the top, back and sides of
15 the vehicle body.

The principal object of this invention is to provide a construction whereby the flexible type of body may be provided with corners of curved or rounded contour, without impairing or interfering with the flexibility of the body. To this end, I provide in my preferred form of embodiment, rigid corner posts which are so formed as to provide for the rounded contour between the
20 top, sides and back and also between the sides and the back, the upper ends of the posts being spherical to give the corners a
25 "domed" contour.

In the accompanying drawings, Fig. 1 is
30 a side elevation of the rear part of the skeleton frame of a flexible body showing my invention applied thereto; Fig. 2 is a rear elevation of the same; Fig. 3 is a plan elevation of the parts shown in Figs. 1 and
35 2, and Fig. 4 is an enlarged detail view showing a form of Weymann joint.

In the drawings, I have represented the side sills 5 of the chassis frame somewhat diagrammatically. Arranged transversely
40 to, and secured on, these side sills are a plurality of spaced transverse base members 6. As in the Weymann body, the skeleton frame is built up on these transverse supporting pieces and the various pieces of the
45 skeleton are flexibly connected together so that the body is free to weave and warp with the chassis frame. In the drawings, I have shown only the rear portion of the skeleton frame in order to illustrate the preferred
50 form of embodiment of my invention and the general construction of the flexible body will be understood from the following description of my improvement.

Each of the corner posts comprises a vertical side member or piece 8 and a vertical

rear piece 9 which are curved inwardly at their upper ends and rigidly connected together from top to bottom by a metal plate 10, preferably formed of aluminum and sufficiently rigid so that the two posts 8
60 and 9 and the plate form a rigid unit. The upper end of the plate is somewhat spherical or dome-shaped, and below the dome contour the plate is curved transversely in order that the rear corners of the body may have 65 a curved contour, while the sides of the top are also curved and merge into the sides of the body. The upper ends of the vertical pieces 8 and 9 of each post contact with each other but the lower end of the vertical
70 piece 9 is preferably spaced from the lower end of the companion piece 8 and also from the rear transverse piece 6. The lower ends of the vertical pieces 9 of the two posts are spaced apart by a connecting piece 75 12 the ends of which are flexibly connected to the lower ends of the pieces 9 by means of the thin sheet-metal plates or brackets 13, which constitute the well-known Weymann form of connection, these connections being 80 designed to permit each piece of the body to be moved relative to the adjoining pieces when the body moves. The upper ends of the posts are connected by the usual metal plates 14, (like plates 13) to the ends of the
85 transverse piece 15. The rear window frame 16 is also flexibly mounted on the vertical pieces 9 by the same type of connections.

In Fig. 4 I have illustrated, on an enlarged and exaggerated scale, a form of Weymann flexible connection, and as shown in this view the adjacent ends of two of the wooden pieces 9 and 12, for example, of the skeleton frame are spaced slightly
90 apart and are connected together in spaced relation by two thin flexible metal plates 13^a and 13^b secured against the opposite sides of the wooden pieces by bolts or rivets
95 22 which extend through holes 23 in the metal plates and wooden pieces, one or more of the holes in the wooden pieces being slightly larger than the bolt or bolts extending therethrough. In this figure, part
100 of the metal plate 13^a is shown broken away to show part of the other metal plate 13^b in dotted lines.

The various other frame members and parts, such as the top side rail 17, the intermediate side piece 18, and the wheel arch 110

rail 19, are flexibly connected to the vertical piece 8, as shown in Fig. 1. The wheel arch rail 19 is provided with a panel 20, preferably formed of metal, which is rigidly secured to it and to a bottom piece 21.

From the foregoing description it will be obvious that the corner posts are so constructed that each corner post forms a rigid unit and affords the construction of a flexible body designed along the desired curved lines. These posts are flexibly connected to the other parts of the body so that they do not interfere with the weaving or warping action of the body.

15 I claim:

1. In a road motor vehicle body constructed to weave with the chassis frame, the combination of a skeleton frame comprising vertical members and connecting members joined thereto, each member being movable relative to the adjoining members, and corner posts each consisting of two spaced apart pieces united together to form a rigid unit with the adjoining pieces of the skeleton frame movable relative thereto.

2. In a road motor vehicle body constructed to weave with the chassis frame, the combination of a skeleton frame comprising vertical members and connecting members joined thereto, each member being movable relative to the adjoining members, and corner posts each consisting of two spaced-apart pieces and a plate connecting said pieces to form a rigid unit.

3. In a road motor vehicle body constructed to weave with the chassis frame, the combination of corner posts each consisting of two spaced-apart pieces connected together to form a rigid unit, connecting pieces between the posts, means for flexibly connecting said connecting pieces to the posts, side pieces, and means for flexibly connecting said side pieces to the posts.

4. In a road motor vehicle body constructed to weave with the chassis frame, the combination of corner posts each comprising a vertical rear piece and a vertical side piece curved at their upper ends and arranged at an angle to each other, and a curved plate connecting said vertical pieces to form a rigid unit, a rear connecting piece between said posts, means for flexibly connecting said connecting piece to said posts, side pieces, and means for flexibly connecting said side pieces to said posts.

5. In a road motor vehicle body constructed to weave with the chassis, the combination of a rear transverse piece secured to the chassis, vertical side pieces, means flexibly connecting the lower ends of said vertical side pieces to said transverse piece, two

vertical rear pieces having their lower ends spaced from said transverse piece and said vertical side pieces, means for rigidly connecting each vertical side piece and its adjacent vertical rear piece together to form a rigid unit, a connecting piece between said vertical rear pieces, means for flexibly connecting said connecting piece to said vertical rear pieces, side pieces, and means for flexibly connecting said side pieces to said vertical side pieces.

6. In a road motor vehicle body constructed to weave with the chassis frame, the combination of a rear transverse piece secured to the chassis, vertical side pieces, means flexibly connecting the lower ends of said vertical side pieces to said transverse piece, two vertical rear pieces having their lower ends spaced from said transverse piece and said vertical side pieces, a curved plate with a spherical contour at its upper end and rigidly connecting each vertical side piece and its adjacent vertical rear piece to form a rigid post, other pieces of the skeleton frame, and means for flexibly connecting said other pieces to said posts.

7. In a road motor vehicle body constructed to weave with the chassis frame, the combination of a skeleton frame comprising vertical pieces and connecting pieces joined thereto, each piece being movable relative to the adjoining pieces, and rigid corner posts each comprising two spaced-apart pieces, a window frame supported between said posts, and means for flexibly connecting said window frame to said posts.

8. In a road vehicle body constructed to weave with the chassis frame, the combination of a skeleton frame comprising vertical members and connecting members joined thereto, each member being movable relative to the adjoining members, and corner posts each consisting of two spaced apart pieces and a curved plate extending the length of the pieces and rigidly connected thereto to form a rigid unit, the adjoining pieces of the skeleton frame being movable relative thereto.

9. In a road motor vehicle body constructed to weave with the chassis frame, the combination of a skeleton frame comprising vertical members and connecting members joined thereto, each member being movable relative to the adjoining members, and corner posts each consisting of two spaced apart vertical pieces having their upper ends curved toward each other and a plate extending substantially the length of said pieces and connected thereto to form a rigid unit.

ALBERT H. WALKER.
